UNITED STATES PATENT OFFICE.

OSCAR WALFRID HULT, OF STOCKHOLM, SWEDEN.

BOAT-MOTOR.

1,138,294.

Specification of Letters Patent.

Patented May 4, 1915.

Application filed August 25, 1914. Serial No. 852,577.

To all whom it may concern:

Be it known that I, OSCAR WALFRID HULT, subject of the King of Sweden, and resident of 1 Inedalsgatan, Stockholm, in the Kingdom of Sweden, engineer, have invented certain new and useful Improvements in Boat-Motors, of which the following is a specification, reference being made to the accompanying drawing.

19 The present invention relates to the balancing of such boat motors, in which the work is carried out by a reciprocating piston or, as the case may be by several reciprocating pistons acting in the same direction.

15 On the accompanying drawing the invention is by way of example shown applied to so-called outboard motors (which, however, may also be mounted inboard).

20 Figures 1 and 2 show each a vertical section of such a motor.

In accordance with Fig. 1 the motor shaft A is provided with two cranks which are situated diametrically with regard to the shaft and which cranks are, by means of connecting rods B and C, connected to pistons D and F. D is the working piston, which is directly acted upon by the motive charges in the cylinder E. F is a balancing piston, which is adapted to annul the momentum of the piston D when turning in the end positions, while at the same time constituting the fastening of the upper end of the connecting rod J of the propeller shaft I. The cylinder H of the piston F will thus, through the piston, serve as a guide for the upper end of the connecting rod J.

In the motor, shown in Fig. 1, the two cranks of the motor shaft are of equal lengths. The invention may, however, also be carried out advantageously according to Fig. 2, that is to say so, that the crank of the piston F is shorter than that of the piston D. This is advantageous for the reason that the greater weight which loads the piston F, because this also carries the connecting rod J, can thereby be balanced. A part of the weight of the connecting rod J can also—as is usual—be balanced by a counter-weight on the crank portion of the driving or propeller shaft I. The working piston and the balancing piston may evidently have different diameters.

By means of the arrangement according to Fig. 2 the diameter of the crank casing

becomes considerably less, which is an advantage, for instance, in outboard motors.

Although the invention is on the drawing shown as applied to outboard motors, it may also advantageously be applied to inboard motors, similar to the motors shown in Figs. 1 and 2. In this case the propeller portion of the motor can be passed down through the bottom of the boat through a vertical drum. The invention may also be applied to other inboard motors as well as to other kinds of motors which should run as vibrationless as possible.

Having thus described my invention what I claim as new and desire to secure by Letters Patent is:—

1. In a motor the combination of a working piston, a motor shaft having a crank connected with said piston, a balancing piston also connected with a crank on said motor shaft, and a driving shaft having a crank connected with said balancing piston.

2. In a motor the combination of a working piston, a balancing piston having its axis substantially in alignment with the axis of said working piston, a motor shaft located between said pistons, means for connecting said pistons to diametrically opposed cranks on said motor shaft, a driving shaft, and means for operating said driving shaft from said balancing piston.

3. In a motor the combination of a working piston, a balancing piston having its axis substantially in alignment with the axis of said working piston, a motor shaft located between said pistons, means for connecting said pistons to diametrically opposed cranks on said motor shaft, the crank connected to the balancing piston being shorter than the one connected to the working piston, a driving shaft, and means for operating said driving shaft from said balancing piston.

4. In a boat motor, the combination of a working piston, a balancing piston having its axis substantially in alignment with the axis of said working piston, a motor shaft located between said pistons, connecting rods connecting said pistons to diametrically opposed cranks on said motor shaft, a propeller shaft, and a connecting rod connecting said balancing piston to a crank on said propeller shaft.

5. In a boat motor, the combination of a working piston, a balancing piston having

its axis substantially in alinement with the axis of said working piston, a motor shaft located between said pistons, connecting rods connecting said pistons to diametrically opposed cranks on said motor shaft, the crank connected to the balancing piston being shorter than the one connected to the working piston, a propeller shaft, and a connect-

ing rod connecting said balancing piston to a crank on said propeller shaft.

In witness whereof I have hereunto set 10 my hand in presence of two witnesses.

OSCAR WALFRID HULT.
